UNITED STATES PATENT OFFICE.

GEORGE H. FIFIELD, OF WHITING, INDIANA.

ART OF DISTILLING PETROLEUM OILS.

Application filed April 26, 1920. Serial No. 376,630.

To all whom it may concern:

Be it known that I, GEORGE H. FIFIELD, a citizen of the United States, residing at Whiting, in the county of Lake and State 5 of Indiana, have invented a new and useful Improvement in the Art of Distilling Petroleum Oils, of which the following is a specification.

The present invention relates to the art 10 of distilling petroleum oils and more particularly to the distillation of such oils with fire and steam. It will be clearly understood from the following description, which is illustrated by the accompanying 15 drawings, in which—

Figure 1 is a vertical section longitudinally thru the still on a broken line as indicated in Fig. 3.

Figure 2 is a horizontal section on the 20 line 2—2 of Fig. 1, and

Figure 3 is a vertical transverse section on the line 3—3 of Fig. 2.

Referring more particularly to the drawings, the numeral 5 indicates a shell still 25 provided with the usual feed and discharge pipes 6 and 7 and with a steam inlet pipe 8, which extends into the still as perforated pipe 9, thru which steam may be admitted into the still near its bottom. The 30 still is likewise provided with a suitable overhead line 10 through which vapors discharge to a condenser. A suitable gauge 11 may be provided for observing the level of the still contents.

35 A plurality of tubes 12 pass thru the still longitudinally, opening at one end into a space 13 at one end of the still setting and at the other into the flue 14 leading to the stack, for example. The combustion gases from the fireplace 15 play against the bottom of the still 5 and pass back to the space 13, from which they pass thru the tubes 12 to the flue 14. A hollow buttress 16 serves to support the end of 40 the still 5 and also to protect the pipes 6, 7 and 8, which pass thru it, from the direct heat of the combustion gases. The tubes 12 have a combined surface greater than the heated surface of the still proper, 45 and are arranged in two groups, spaced from each other by a suitable distance, say one foot, this space being sufficient to provide passageway between the groups of tubes. The tubes are spaced from the bottom 50 of the still, being arranged near the central line of the still, the top row of tubes

being, if desired, slightly above this line. In operation there is normally a body of oil in the still extending above the tubes, a large bulk of which is between the directly heated still surface and the lowermost bank of tubes. One or more brackets or supports 17, preferably suspended from the top of the still, aid in supporting the tubes and prevents sagging.

In operation for the production of viscous lubricating oils a still, for example, 12 by 40 feet, is charged to a point above the tubes with a stock having a density of, say 29.6° Bé. and a viscosity of 60 to 64 60 at 100° F., and is heated by combustion in the fireplace 15 while steam is admitted to the bottom of the still. The combustion gases pass along the bottom of the still where a relatively high average temperature 65

(above 1000—1100° F., for example) prevails to the space 13 and from there thru the tubes 12 at an average temperature between 300 and 400° lower to flue 14. The 70 temperature of the liquid in the still will be approximately 50 to 75° less than that of the gases leaving the tubes substantially all of the available heat of the gases having been imparted to the oil in the still. The tube surface is large relative to the 75 heated still surface, there being, for example, 40 to 60 tubes of any suitable diameter, say 4—8 inches, while the directly heated area of the drum approximates about $\frac{1}{4}$ th of its cylindrical surface. The tube 80 surface may be six to eight times the directly heated surface of the drum. The charging stock is constantly supplied to the still during distillation in proportion to the quantity of distillate produced, and the distillation continues until the still contents have the desired viscosity, say 240 at 85 100° F. The contents of the still may be then discharged and subjected to the usual acid treating processes. If desired, and particularly in shorter stills the combustion gases may be passed in one direction 90 through one set of tubes and returned through the other, suitable baffles being provided for this purpose.

The distribution of the heat in accordance with the invention appears to materially decrease the breaking down or loss of viscosity of the residues in the still, as the 95 yield of residues of a determined viscosity 100 from a certain quantity of stock is considerably greater when the distillation is car-

- ried out as above described than when the distillation is carried out in an ordinary shell still. Furthermore the running capacity of the still is much greater than with stills of the ordinary shell type. It is readily apparent that the still may be utilized in the distillation of oils without steam, particularly in such distillation processes as the skimming of crudes, etc.
10. What I claim as new and desire to secure by Letters Patent is:
1. A shell still, means for supplying steam at the bottom of the still; means for heating the lower portion of the still surface; a plurality of tubes passing thru the still near the center line of the still providing a heating area greater than the heated area of the still surface and means for heating the surface of said tubes to a lower temperature than the temperature of the heated still surface.
  2. A shell still, means for supplying steam at the bottom of the still, means for heating the lower portion of the still surface, a plurality of horizontal tubes passing longitudinally through the still near the center line of the still providing a heating area greater than the heated area of the still surface and means for heating the surfaces of said tubes to a lower temperature than the temperature of the heated still surface.
  3. A shell still, means for supplying steam at the bottom of the still, means for heating the lower portion of the still surface, a plurality of horizontal tubes passing longitudinally thru the still near the center line of the still providing a heating area greater than the heated area of the still surface, said tubes being spaced from the bottom of the still, and means for heating the surfaces of the tubes.
  4. A shell still, means for supplying steam at the bottom of the still, means for heating the lower portion of the still surface, a plurality of horizontal tubes passing longitudinally thru the still near the center line of the still providing a heating area greater than the heated area of the still surface, said tubes being spaced from the bottom of the
- still and arranged in two horizontally spaced groups, and means for heating the surfaces of the tubes and the bottom of the still.
5. A shell still, means for supplying steam at the bottom of the still, means for heating the lower portion of the still surface, a plurality of horizontal tubes passing longitudinally thru the still near the center line of the still providing a heating area greater than the heated area of the still surface and means for conducting heated gases first over the bottom of the still and then thru the tubes.
6. The process of fire and steam distillation of hydro-carbon oils which consists in maintaining a body of oil in a confined space, applying heat at an average temperature above 1000-1100° F. at the bottom of the confined body of oil, injecting steam thereinto near its bottom and applying heat to an area in excess of that of the bottom of the oil body to which heat is applied, said area being arranged in distributed zones within the oil intermediate its surface and its heated bottom at an average temperature more than 300° less than that applied at its bottom, and withdrawing the evolved vapors.
7. The process of fire and steam distillation of hydro-carbon oils which consists in maintaining a body of oil in a confined space, passing a heating medium at high temperature in heat-conductive contact with the bottom of the body of oil whereby heat is imparted thereto and the temperature of the heating medium lowered, conducting the heating medium after contact with the bottom of the body of oil through the latter and in heat conductive contact with the oil above the vertical center of the body of oil and below its upper level and over an area in excess of that of the bottom of the oil body to which heat is applied, injecting steam into the body of oil near the highly heated surface, and withdrawing the evolved vapors.

GEORGE H. FIFIELD.
